UNITED STATES PATENT OFFICE

2,439,431

SHANK REINFORCED SHOE CONSTRUCTION

Melville Kaufmann, Los Angeles, Calif.

Application September 5, 1944, Serial No. 552,725

4 Claims. (Cl. 36—8.5)

1

My invention relates to the art of manufacturing shoes and has particular reference to a new and novel casual shoe or slipper construction and the method of making the same. In the art of manufacturing shoes, particularly shoes of the type known as casual, several methods of construction have been employed:

1. Forming an upper upon a last and attached directly to an insole member, to which is then attached an outsole member usually formed of relatively stiff leather forming the outsole or tread portion of the shoe, the outsole being secured to the insole by suitable stitching at the edges of the sole.

2. The forming of an outsole of relatively thick padded material which is attached to an upper and often referred to as a Chinese type slipper.

3. Shoes or slippers of the type having an upper lasted to an insole, provided with a midsole of thick cushioning material with associated heel lift covered about the edges as a single unit, and an outsole is attached to the lower surface of the midsole. This type of shoe is usually flat soled, although an arch appearance is obtainable by notching the heel lift.

It is to a new and novel casual shoe adaptation of the midsole type construction that the instant invention is directed, particularly embodying a spring heel and cushioning pad combination covered by an edge strip giving the effect of a single unit, and with an ornamental arch effect.

Another object of the invention is to provide a shoe or slipper of the character identified wherein the midsole is adapted to receive a substantially rigid supporting member or shank extending longitudinally from that portion of the midsole embracing the breast of the heel forward to a point just behind the tread of the sole.

Another object of the invention is to provide a casual shoe of the character set forth wherein the heel lift is formed and positioned in relation to the cushioning pad to provide an arch.

It is still another object of my invention to provide a casual shoe of this character having a member designed to give internal stability to the shoe whereby the attractiveness of an arched outsole combined with the features of an internal heel lift is achieved.

A still further object of the invention is to provide a method of constructing a casual slipper including an upper, an arched outsole, and a midsole interposed between the upper and outsole and embodying a heel lift, wherein said arch is adequately supported by interposing a substan-

2

tially rigid shank member between the midsole and the upper.

An additional object is to embody additional support in a shoe of the character described by extending the heel lift on the outside of the shoe and thus enable the shoe to resist any tendency of the foot to turn out.

Other objects and advantages will be apparent from a study of the following specification read in connection with the accompanying drawings.

In the drawings:

Figure 1 is a side elevational view partly in section of a shoe constructed in accordance with my invention.

15 Figure 2 is a section taken on the line 2—2 of Figure 1 showing the midsole in plan together with the positioning of the shank thereon, in accordance with my novel shoe construction.

Figure 3 is a cross section taken on the line 3—3 of Figure 2 showing the forward portion of the shank.

19 Figure 4 is a cross section taken on the line 4—4 of Figure 2 showing the shank in the center.

20 Figure 5 is a side elevation showing the inner side of a shoe constructed in accordance with the invention.

Figure 6 is a bottom plan view showing particularly the diagonal shaping of the heel lift.

Referring to the drawings, I have illustrated a 30 shoe which includes an upper 1 which may be formed in a conventional manner, i. e., lasted, and constructed of leather, cloth, or similar materials and may have a stiffened counter 3 and toe 5 if desired. Attached to the upper is an insole 7 which may be stitched or cemented to the upper.

35 A midsole 9 may be constructed entirely separate from the upper. It may comprise a pad 10 preferably cut to substantially conform with the shape of the sole of the desired finished shoe. 40 Such pads are ordinarily made of a cushioning material such as felt, cork, sisal, fiber, rubber, or other resilient composition.

The midsole may be further characterized by having associated with the pad 10 a spring heel 45 lift or elevated supporting member 12 attached thereto as an integral part thereof. This lift may be formed of felt or similar suitable materials, e. g. cork, fiber, sisal, rubber, wood or plastic. As shown in Figure 6, its forward edge should 50 be formed at an angle to give a larger area of elevated support to the outer edge of the foot. Such shaping makes for an additional margin of support most desirable in casual shoes and heretofore overlooked. The heel lift is further 55 characterized by being beveled or tapered up-

wardly as at 13 to provide an arch 14 in the midsole and create the spring effect in the heel.

The midsole may have an edge covering 15 of flexible leather, fabric, rubber or other sheet material serving the double purpose of finishing and decorating the raw edges of the cushioning material and serving to aid in retaining the shape of the midsole and in securing it to the other associated parts of the shoe. The covering material selected should be wide enough to be inturned and secured to the upper and lower surfaces of the cushioning pad or midsole, as shown in Figure 2, and the lower surface of the heel lift 12, wherein the edges 16 of the material are illustrated as being turned inwardly and cemented, or otherwise secured, to the surface of the cushioning pad.

It is to the arched midsole unit so formed and comprising the pad and beveled heel lift that my outsole 21 is attached. The outsole may be leather, rubber, or other durable wearing material.

To insure stability of the arched portion of the outsole of the shoe created in accordance with my invention and the attendant decorative and structural advantages in the shoe a stiff shank element 22 is positioned between the upper and midsole. Such element 22 is preferably arched and positioned to extend from about the center of the heel to a point just back of the tread of the sole, thereby resulting in reduction of weight and pressure on the arched portion of the midsole and outsole. The positioning of the shank relative to the midsole is shown in Figure 2. This shank may be made of wood, metal, plastics, hard rubber and/or other stiff and otherwise suitable material.

It is preferable to form the shank 22 with a relatively thick center section 23 convex at the bottom and flat at the top, merging this section in thinner flat ends 24. The shank will ordinarily be cemented down to the pad of the midsole, and as the pad is yielding the convex surface can settle into the pad without cutting it at the region where the shank sustains the greatest stress. As shown, this shank is merely interposed between the insole 7 and the midsole 9, and bridges the arch 14.

It will be apparent that cementing, sewing, stapling or equivalent methods may be employed for attaching the outsole to the midsole. The heel lift may be attached by such various means to the midsole pad either above or below it, or formed as an integral part thereof. The covering for the unit comprising the heel lift and pad may be cemented and/or sewn to said unit. The positioning of the arched member on said unit may be rendered secure and the upper and insole attached to said midsole by any similar means.

It will thus be observed that I have provided a casual shoe or slipper construction having the comfort and advantages embodied in a midsole with a built in heel lift and yet so constructed as to receive and support an arched outsole. The construction of the shoe is further characterized by the presence of a rigid internal arched supporting element cooperating to give stability to the structural and decorative advantages of the arched outsole.

The diagonal tapered forward edge 13 of the heel lift provides the arch form extending diagonally across the shoe as shown at 25 in Figure 6. The outsole covers the entire lower surface of the shoe.

An arch is desirable, but in this type of construction would break down without a support. The heel is too low to notch it for the appearance

of an arch, an expedient which is undesirable because it weakens the forward section of the heel wedge, and moreover, requires too long a wedge, at least in a man's shoe, which the present construction contemplates.

In the present construction, I have achieved a low heel of substantially normal surface area on the inside and an extension on the outside, a low arch to break the flatness of the midsole type shoe, and a simple but effective shank for sustaining the stresses on the arch.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures.

Having described my invention, what I claim as new and desire to secure by Letters Patent is:

1. In a casual shoe construction, an upper, the lower edges of which are turned inwardly and secured to the outer surface of an insole, a midsole comprising a sole portion of relatively thick cushioning material and a heel lift with a lower face tapered to form an arched surface, said heel lift being formed to provide a longitudinally longer area of support for the outer portion of the heel than the inner, said midsole being shaped to extend completely over the lower surface of said insole, a stiff supporting element positioned between the insole and midsole unit to distribute pressure on the shoe between the tread and heel and thereby relieve stress on the arched portion, a covering of relatively thin material turned in about and covering the edges of the midsole, means securing the upper surface of said midsole and said thin covering to the insole, an outsole coextensive with the area of the midsole, said outsole being attached to said midsole unit and conforming to the arch therein.

2. In a casual shoe construction, an upper, the lower edges of which are turned inwardly and secured to the outer surface of an insole, a midsole comprising a sole portion of relatively thick cushioning material and a heel lift with a lower face tapered and cut to form an arch with the sole portion, said midsole being shaped to extend completely over the lower surface of said insole, a stiff shank positioned between the insole and midsole extending from the center of the heel area to a point just back of the tread of the sole to distribute pressure on the shoe between the tread and heel and thereby relieve stress on the arch, said supporting member further characterized by being flattened on top, vertically thickened at its center, tapered at the points of contact with the tread and heel of the shoe and having its thickened portion convex in cross section on the lower surface to normally ride upon the sole portion and to nest into the material of the midsole when under pressure a covering of relatively thin material about the edges of the midsole, means securing the upper surface of said midsole to the insole and said covering, and an outsole coextensive with the area of the midsole, said outsole being attached to said midsole and conforming to said arch.

3. In a shoe construction of the character described comprising an insole and a midsole in the arch area of the shoe, a shank approximately one-third of the width of the narrowest portion of the insole and substantially rectangular in hori-

zontal section yieldably disposed between the insole and the midsole longitudinally along the arch, said shank having a convex undersurface normally riding upon the upper surface of the midsole yieldably nesting therein in use, and a substantially flattened upper surface adjacent the insole, said shank having relatively thin substantially flattened vertically tapered end portions merging into the main central body of the arch positioned to extend lengthwise of the shoe from the center of the heel to a point just rearward of the tread sole.

4. In a shoe construction of the character described comprising an insole and a midsole in the arch area of the shoe, a shank approximately one-third of the width of the narrowest portion of the insole and substantially rectangular in horizontal section yieldably disposed between the insole and the midsole, a heel lift providing a longitudinally longer area of support for the outer portion of the heel than the inner portion, said shank extending longitudinally along the shoe and diagonally relative to the arch, said shank having a convex undersurface normally riding upon the upper surface of the midsole yieldably nesting therein in use, and a substantially flattened upper surface adjacent the insole, said shank having relatively thin substantially flattened vertically tapered end portions merging into the main central body of the arch positioned to extend lengthwise of the shoe from the

center of the heel to a point just rearward of the tread of the sole.
